FISH AQUARIUM

Gary L. Anielak, 325 Buck St., Collinsville, Ill. 62234

Filed Apr. 10, 1972, Ser. No. 242,888

Term of patent 14 years

Int. Cl. D30—02

U.S. Cl. D30—9

Fig. 1.

Fig. 2.

Fig. 3.

Fig. 4.

FIG. 1 is a top plan view of a fish aquarium, showing my new design;

FIG. 2 is a side elevational view, the opposite side being substantially a mirror image thereof;

FIG. 3 is a left end elevational view of FIG. 2; and

FIG. 4 is a right end elevational view of FIG. 2.

Portions of the drawing figures are diagonally lined to indicate transparency.

I claim:

The ornamental design for a fish aquarium, as shown and described.
